UNITED STATES PATENT OFFICE.

MARLOWE W. STEVENS, OF HELLIER, KENTUCKY.

CUT-OUT-SWITCH LOCK.

Application filed October 23, 1924. Serial No. 745,483.

This invention relates to new and useful improvements in switches, and particularly to switches for use in connection with third rails or overhead trolley wires, in mines.

5 One object is to provide a switch of this character, which is especially adapted for use as a cutout, and which automatically locks in open position, to protect the workmen from high tension currents, when coming into contact with the rail or wire.

10 Another object is to provide a cutout switch arranged to be readily swung into and out of operative position, and being provided with a keeper adapted to receive the latch or lock bolt of a lock, whereby to hold the switch out of position, while the wire is being operated upon.

15 Another object is to provide a movable rail or wire section which has means for forming proper electrical contact with the remainder of the rail or wire.

20 Other objects and advantages will be apparent from the following description when taken in connection with the accompanying drawing.

In the drawing:

Figure 1 is a side elevation of a portion of an elevated trolley wire, showing the cutout switch in closed position.

25 Figure 2 is a vertical transverse sectional view on the line 2—2 of Figure 1.

Figure 3 is a vertical transverse sectional view on the same line as that of Figure 2, but showing the switch in open and locked position.

30 Figure 4 is a horizontal sectional view on the line 4—4 of Figure 1.

Referring particularly to the accompanying drawing, 10 and 11 represent the ends of a trolley rail, which are suspended by the support or hanger 12. In the lower portion of the center of the support or hanger there is formed a longitudinal recess 13, and disposed within this recess is the upper edge of the movable rail section 14, a shaft 15 being disposed longitudinally through the upper portion of the section and through the end walls of the recess, whereby to pivotally support the section 14, for lateral swinging movement into and out of alinement with the rail ends 10 and 11. In the intermediate portion of the upper part of the section 14 there is formed a recess 16, and secured in covering relation to this recess is a longitudinally slotted plate 17, which forms the

keeper for the lock 18, which is mounted in a recess 19, in one side of the support or hanger 12. One end of the shaft 15 is bent into crank form, as shown at 20, and is provided with a hand grip 21, which is adapted to be grasped to rock the shaft and thereby swing the section 14 into and out of alinement with the rail ends 10 and 11. In the mutually adjacent ends of the rails 10 and 11 there are formed the recesses 22, and secured in each of these recesses is a spring contact finger 23. To each end of the movable section 14 there is secured a contact finger 24 which engages with a finger 23, when the section is swung into alinement with the rail ends 10 and 11.

40 The lock 18 is provided with a bolt 25, controlled by the key 26, and normally urged outwardly by a spring 27, into position to engage in the slot of the keeper 17, when the section 14 is swung upwardly out of alinement with the rail ends 10 and 11.

45 By reason of the fact that the contact fingers 23 are mounted within recesses in the ends of the rail sections 10 and 11, said fingers will not be easily engaged and broken, or displaced.

50 The fact that the switch section 14 is locked in open position, renders the working on the rail ends 10 and 11 safe for the workmen, as the current is broken when the section 14 is swung out of alinement with the sections 10, and 11, and away from the contacts 23.

55 The outer end of each of the rail sections 10 and 11 is formed with a recess 28, within which is disposed a spring pressed wedge member 29, for holding the end of a wire 30 inserted in said recess.

60 The support or hanger 12, as well as the upper portion of the movable section 14, are formed from insulation.

65 What is claimed is:—

70 1. The combination with a support having a central recess in its lower portion, rail sections carried by the support and terminating at the ends of the recess, a movable rail section pivotally supported within said recess for movement laterally into and out of alinement with the first rail sections, a lock on the support, and means on the movable section for engagement with said lock for holding the movable section out of alinement with the first sections.

75 2. The combination with a support having

a central recess in its lower portion, rail sections carried by the support and terminating at the ends of the recess, a movable rail section having an upper portion of insulation pivotally supported in said recess, a keeper carried by said insulated portion of the movable section, and a lock carried by the

support and including a bolt for engagement with said keeper for holding the movable section out of alignment with the first rail sections, at times.

In testimony whereof, I affix my signature.

MARLOWE W. STEVENS.
